UNITED STATES PATENT OFFICE.

COLLINS ARNOLD, OF ALBANY, NEW YORK.

DESIGN FOR AN ABDOMINAL BAND.

SPECIFICATION forming part of Design No. 30,458, dated April 4, 1899.

Application filed February 9, 1899. Serial No. 706,121. Term of patent 7 years.

To all whom it may concern:

Be it known that I, COLLINS ARNOLD, a citizen of the United States, residing at the city of Albany, county of Albany, and State of New York, have invented and produced a new and original Design for Abdominal Bands, of which the following is a specification, reference being had to the accompanying drawing, showing a perspective view of an abdominal band embodying my new design.

The design consists in the ornamental configuration of the band.

The band comprises the body 1 and the tabs 2, 3, 4, 5, 6, and 7, the latter two depending from the lower edge of the cylindrical body. The body is cylindrical in form, and the tabs 2, 3, 4, and 5 project from the upper edge of the body, as shown.

The leading feature of the design consists in the four tabs projecting upwardly from the upper edge of the cylindrical body of the band and the two tabs depending from the lower edge thereof.

What I claim as new, and desire to secure by Letters Patent, is—

The design for an abdominal band herein shown and described.

In testimony whereof I have hereunto set my hand this 4th day of February, 1899.

COLLINS ARNOLD.
